UNITED STATES PATENT OFFICE.

WILLIAM C. B. SPARRY, OF NEW YORK, N. Y.

DESIGN FOR A PARASOL OR LIKE ARTICLE.

SPECIFICATION forming part of Design No. 25,368, dated April 7, 1896.

Application filed July 30, 1895. Serial No. 557,639. Term of patent 7 years.

To all whom it may concern:

Be it known that I, WILLIAM C. B. SPARRY, a citizen of the United States, residing in the city, county, and State of New York, have invented and produced a certain new and original Design for Parasols, Umbrellas, and the Like, of which the following is a specification.

The new design relates to the shape and surface ornamentation of oblong substantially rectangular parasols, umbrellas, and analogous shades, as parasols for baby-carriages.

The new design is shown in the accompanying drawing, which is a perspective view of a baby-carriage parasol, showing the obverse of the new design.

The distinctive features of the new design are an oblong eight-sided convex obverse side A, a vertical pendent border B, a bulbous annulus E on the obverse side, outlines F F, G G, and H H H H, points c d e in the outlines, parts f g h on the obverse side, lines i j, fringe k, scallops l, and flutes I. These features have the shape, ornamentation, and appearance shown, the outlines F F being long and of slightly concave curvature, the out-

lines G being long and of slightly concave curvature, and the outlines H being short and of relatively great concave curvature, the parts f being substantially triangular and of acute angularity, the parts g being substantially triangular and of less angularity, and the parts h being substantially triangular and of still less acute angularity. The lines i and j are straight and diverging. The outlines F F in their general extension are at substantially right angles to the outlines G G in their general extension, and the outlines H H in their general extension are at substantially angles of forty-five degrees to the other outlines and substantially at right angles to each other.

What I claim is—

The design for parasols, umbrellas and the like, substantially as herein described and shown in the drawing.

In witness whereof I have hereunto signed my name in the presence of two subscribing witnesses.

WILLIAM C. B. SPARRY.

Witnesses:

J. C. W. MANUEL,
